UNITED STATES PATENT OFFICE.

ADOLPH STUBER AND ERNEST E. UNDERWOOD, OF ROCHESTER, NEW YORK, AS-
SIGNORS TO EASTMAN KODAK COMPANY, OF ROCHESTER, NEW YORK, A CORPORA-
TION OF NEW YORK.

MOTION-PICTURE SCREEN.

Application filed June 19, 1926. Serial No. 117,096.

This invention relates to motion picture screens, and particularly to screens for small sized pictures for home use. One object is to provide a screen in which the screen surface may be protected from damage when not in use. Another object is to provide such a screen which may be quickly and easily positioned to receive pictures. Another object is to provide a self-contained outfit which is attractive in appearance. Still another object is to provide a simple latch reversing structure adapted for holding the screen surface in a protected or exposed position relative to the frame, and other objects will appear hereinafter, the novel features being pointed out in the claims at the end thereof.

In the drawings, wherein like reference characters denote like parts throughout.

Fig. 1 is a front elevation of a screen constructed in accordance with and illustrating one embodiment of our invention.

Fig. 2 is an enlarged fragmentary detail section on line 2—2 of Fig. 1;

Fig. 3 is a similar view on line 3—3 of Fig. 1; and

Fig. 4 is a similar view on line 4—4 of Fig. 1.

In the preferred embodiment of our invention, shown in Fig. 1, the motion picture screen consists of a support designated broadly by 1. This support comprises a frame member having sides 2, a top 3, and a bottom member 4. Across the back of the frame thus formed there is a protecting wall 5, which may be attached to the frame members in any suitable manner. In the present embodiment a rabbet 6 is provided in the frame for receiving the edges 7 of the protecting wall, and the beading 8 is fastened over the edge 7, and a portion of the frame 2 to hold the parts in position. The frame and the back wall 5 form a shallow box-like structure.

For supporting the above described member on a table or similar flat surface we provide a pair of legs 9 which are adapted to swing upon pins 10 carried by the bottom frame member 4. These legs are provided with pairs of bearing surfaces 11. On the right hand side of Fig. 1 the leg is shown in a folded position in which it lies parallel to and against the bottom member 4 to support the screen. The legs are swung upon their pivots to the position shown at the left hand side of Fig. 1, in which the leg lies at substantially right angles to the frame member 4.

The screen surface 12 may be of any well known type, and stretched upon a member 13, which is preferably provided on the opposite side of the protective covering 14. This member fits into a shallow box formed by the frame and the back 5, and may be held to the support by the following mechanism.

As shown in Fig. 3, the top bar 3 of the frame is provided with a latch 15. This latch is carried by a stud 16, which is supported in the top bar 3. Latch 15 terminates at one end in a hook 17, and at the other in a handle 18 which projects slightly from the face 19 of the frame 1 so that it may be easily manipulated. As shown in Fig. 1 a pair of these latches is preferably used. The hooks 17 are adapted to engage pins 20, which are carried to the member 13. This member in the present embodiment of our invention is provided with four of these pins 20,—two at the top to be engaged by the latch members 15 and two at the bottom to engage in apertures 31, which, as shown in Fig. 4, are preferably surrounded by facing plates 22.

The pins 20 are spaced on member 13 in such a way that the screen surface 12 may be positioned to lie in a protected position inside of the shallow box formed by the support, or in exposed position, in which it faces away from the support in position for receiving a projected image, as is shown in Fig. 1.

As best indicated in Figs. 2 and 4, we have provided a flange 26 extending around the inside of the frame. This flange is positioned so as to contact with the beading 27, which holds the screen surface 12 against member 13, or of the beading 28, which extends around the protective sheet 14 covering the opposite side of member 13. When the screen is placed in the frame facing the back 5 it is spaced from the back by the contacting flange 26 and beading 27, and these members also tend to keep out dust and dirt.

The operation of the screen is simple. When it is desired to project pictures upon the screen surface 12, the latches 15 are swung out by the handle 18, thus causing the sides 25 of the latches to cam out the pins 20. When the latch is swung from the position in full lines in Fig. 3 to that shown in dot and dash lines, the top members 20 are released and member 13 may be removed from the frame by withdrawing the bottom pins 110

20 from the apertures 21. The screen may be then reversed and reinserted into the frame where it will be held with the screen surface 12 exposed by returning the latches 5 15 to their initial position.

For storing the screen when not in use the operation above described may be reversed, thus the screen 12 which may be easily marred by pressure, scratches or dirt may 10 be placed in the box in a protected position. As the legs 9 may be swung into a position parallel with the frame member 4, the screen may be stored in comparatively small space.

Having thus described our invention, what 15 we claim as new and desire to secure by Letters Patent is:

1. In a motion picture screen, the combination with a support including a projecting wall, a screen surface, a member adapted to 20 carry the screen surface, movable connections between the member carrying the screen surface and the support, said movable connections being adapted to support the screen surface in a predetermined position 25 facing, but spaced from the protecting wall of the support.

2. In a motion picture screen, the combination with a support comprising a frame, and back on the frame forming a box-like 30 structure, of latch members carried by the frame, and apertures in the bottom of the frame symmetrically spaced at predetermined intervals, a screen surface, a member carrying the screen surface, and a plurality 35 of pins on the said member spaced similarly to the spacing of the apertures and adapted to be engaged by the latches and by the aper-

tures of the frame whereby the screen surface may be carried in two positions, in one of which the screen may face the bottom of 40 the box and in the other of which the screen may face from the box in position to receive projected images.

3. In a two-part motion picture screen, the combination with one part including a support comprising a shallow box-like structure with the other part including a member adapted to be carried by the support and to extend into the boxlike structure, a screen surface carried by the member, and a movable supporting means carried by one of the two parts and cooperating with the other part, said means being operable to move the screen carrying member from the box. 45

4. In a two-part motion picture screen, the combination with one part including a support comprising a shallow box-like structure with the other part including a member adapted to be carried by the support and to extend into the box-like structure, a screen 60 surface carried by the member, and a movable supporting means carried by one of the two parts and cooperating with the other part, said means including latching members 65 operable between the two members whereby the screen may be retained in the shallow box-like structure with the screen surface protected or exposed relative to the box.

Signed at Rochester, New York, this 16th 70 day of June, 1926.

ADOLPH STUBER.
ERNEST E. UNDERWOOD.
